JOHN DYMOND, OF TORONTO, ONTARIO, CANADA, ASSIGNOR TO LOUIS S. McMURRAY,
OF TORONTO, CANADA.

MACHINE FOR FORMING CRIMPED PIPE-ELBOWS.

1,020,028.

Specification of Letters Patent. Patented Mar. 12, 1912.

Application filed August 28, 1911. Serial No. 646,312.

To all whom it may concern:

Be it known that I, JOHN DYMOND, of the city of Toronto, in the Province of Ontario, Canada, have invented certain new and useful Improvements in Machines for Forming Crimped Pipe-Elbows, of which the following is a specification.

This invention relates to an apparatus for bending sheet metal pipes into elbows and my object is to devise a machine which is capable of simultaneously crimping and bending a length of pipe to form an elbow of any desired angle.

I attain my object by means of a construction in which a length of pipe is supported on a suitable mandrel and fed forward in a step-wise fashion to be acted on by sliding crimpers which at each action impress a circular crimp in the pipe. A suitable bending segment is clamped to the end of the pipe and after each crimp is formed pressure is applied thereto to bend the pipe that fraction of the total bend represented by unity as a numerator and the total number 25 of crimps in the length of the pipe as a denominator.

Figure 1. is a side elevation of my improved machine partly in section. Fig. 2 is a plan view of the same. Fig. 3 is an end view of the same. Fig. 4 is an enlarged longitudinal section of part of the pipe shifting mechanism. Fig. 5 is a plan view partly in section of the pipe shifting cam. Fig. 6 is a face view of the same cam. Fig. 7 is a front view of the rocking lever of the pipe shifting mechanism and connections, partly in section. Fig. 8 is a sectional view of part of the pipe bending mechanism. Fig. 9 is a front view of the bending segment and the 40 clamp thereof. Fig. 10 is a side elevation of the automatic drive-stopping mechanism. Fig. 11 is a rear view of the same parts. Fig. 12 is a face view of the pipe clamp on the sliding head. Fig. 13 is a vertical longitudinal section of the same. Fig. 14 is a front view of part of the machine showing a modification of the crimping mechanism. Fig. 15 is an enlarged section on the line *a—a*, in Fig. 14. Fig. 16 is an enlarged section on the line *b—b*, in Fig. 14. Fig. 17 is a front view of a portion of one of the crimpers. Fig. 18 is an edge view of the same part. Fig. 19 is a front view of one of the clamps and part of a crimper in the po-

sition they assume when a crimp has just been made.

In the drawings like figures of reference indicate corresponding parts in the different figures.

1 is the frame of the machine suitably shaped to support the different parts. On this frame is journaled the driving shaft 2 provided with the usual fast and loose pulleys 3 and 4. This drive shaft by means of the gearing 5 actuates the counter shaft 6 65 journaled centrally and longitudinally of the machine. A clutch 7 of ordinary construction forms a driving connection between the shaft and the gearing. This clutch is provided with the usual clutch 70 shifting mechanism 8. The shaft 6 drives the various parts of the mechanism as will be hereinafter described after the general arrangement of the machine has been set out.

9 is a mandrel carried longitudinally of the machine its rear end being adjustable in the bracket 10. For the most part of its length this mandrel is a simple shaft of comparatively small diameter, but at its forward end is provided with the head 11 80 adapted to fit the interior of a length of stove pipe. This head is held in place by the nut 12, threaded on the end of the shaft so that heads of different size may be employed according to the diameter of the 85 pipe to be operated on.

13 is a sliding head movable longitudinally of the machine on the guides 14. This head is provided on its face with a support 15 adapted to fit within the end of a length 90 of pipe which also it will be noted fits over the mandrel head 11. The length of pipe is clamped on the support 15 by the following mechanism. A clamping ring is formed in two halves 55 pivoted at 56 by their adjacent ends on the head 13. Their other ends 57 are bent upwardly and are engaged by the bent levers 58 fulcrumed on a common fulcrum 59. Between their upper ends the wedge-shaped projection 60 on the hand lever 61 is adapted to engage to separate the ends. This hand lever is fulcrumed on the frame of the machine and is provided with the usual adjusting mechanism 76 by means of which it may be held in any desired position to which it is moved. By drawing on this lever to force the projection 60 between the upper ends of the levers

58 the parts 55 of the clamping band may be drawn together to firmly clasp the pipe against the support 15. A coarse adjustment for the head 13 is provided through 65 the medium of the pinion 16 journaled in a lateral extension of the sliding head provided with a hand wheel 17. This pinion 16 engages the rack 18 on the frame of the machine (see particularly Figs. 2 and 3). By 70 10 this arrangement the front end of the pipe may be brought into proper position for the first crimp.

As the essence of the operation is that a 15 stepwise movement of the length of pipe shall be made, I provide the following mechanism for the purpose. The cam 19 is secured to the counter shaft 6. This cam has a high portion 20 formed thereon. The 20 front of this high portion, which of course takes the greater part of the wear, is formed of a hardened steel sliding block 21, adjustable by means of a screw 22 working through a cross-bar 23 secured to the back of the cam. This cam actuates the lever 24 25 pivoted on the frame of the machine intermediate its ends and preferably provided with a friction roller 25 to engage the cam 19. The upper end of this lever carries a spring actuated sliding dog 26 adapted to 30 engage the ratchet teeth formed on the shifter bar 27 secured to the sliding head 13. This shifter bar is preferably provided on opposite sides with ratchet teeth of different pitch whereby by inverting the bar the 35 amount of forward shift at each step may be varied to suit the space required between the crimps on the pipe. An adjustable stop 28 is provided with which the lever 24 may contact to limit its backward movement to 40 the space of one tooth of the shifter bar.

The pipe which, by the mechanism described, is given a stepwise forward shift is crimped by the following mechanism: Sliding in the guides 29 are a pair of crimpers 45 30, comprising thin steel plates notched to embrace the pipe, as shown, and having thin crimping edges working closely together, as shown particularly in Figs. 1, 2 and 3. These crimpers must operate as closely as 50 possible to the point at which the head 11 supports the pipe and the mandrel must, therefore, be suitably adjusted to bring the head and the crimpers into the proper relationship. The crimpers are operated 55 through the medium of the eccentrics 31 on the counter shaft 6. The eccentric rods are pivotally connected with the ends of the levers 32 which are pivoted intermediate their ends on the frame and at their upper 60 ends are pivotally connected with the crimpers 30. The eccentrics are set so that the crimpers operate immediately after the stove pipe has been shifted one tooth of the shifting bar 27. Immediately after each 65 crimp the pipe is given a slight bend equiv-

alent to that fraction of the total bend represented by unity as a numerator and the total number of crimps in the length of the bent portion of the pipe as a denominator. This slight bend after each crimp is formed 70 through the medium of the following mechanism: The bending segment 33 is clamped to the outer end of the pipe through the medium of the ring 34 to which it is secured and which preferably fits within the 75 pipe as shown particularly in Figs. 8 and 9. A ring 35 fits outside the pipe end and the pipe is clamped to the inner ring by means of the set screws 36 screwed through the ring 35. By imparting an inward and forward 80 push to this quadrant in the direction in which the bend is to take place the slight bend referred to may be imparted to the pipe each time a crimp is formed. For the purpose of moving the quadrant the following mechanism is provided. On the end of the countershaft 6 is secured the cam projection 37 adapted to engage the anti-friction roller 38 secured to the lower end of the lever 39 pivoted intermediate its ends on the frame of the machine. The upper end of this lever is provided with the pin 40 arranged longitudinally of the machine. With this pin is engaged the notched link 41 having a universal joint connection with the friction bar 42 which is secured to the ends of the parts of the swinging frame 43 pivoted on the front end of the machine to one side of the center as shown particularly in Figs. 2 and 3. This friction bar at the 90 point where it engages the segment 33 is provided with a hardened steel plate 44 to take the wear, which plate is grooved to partly receive the edge of the segment. The pin 40 is provided with the stationary collar 46 and the sliding spring actuated collar 47. Between these two collars the notched link 41 fits, as shown, (see particularly Figs. 1, 2 and 8). The parts are thus held in place and the connection between the swinging frame and the lever 39 is of a flexible nature allowing the parts to accommodate themselves to one another. The operation of these parts is as follows: Whenever the cam 37 actuates the lever 39 the frame 43 is 100 105 swung inwardly and toward the right as you face the end of the machine. This imparts a similar movement to the plate 44. This plate engages the edge of the segment and forces the segment slightly in toward 110 the end of the machine and slightly toward the right. The pipe being held between the crimpers the movement of the outer edge of the quadrant plate causes a slight bend of the pipe to take place the extent of which 115 of course depends on the set of the cam 37. The parts are so proportioned that this slight bend is that fraction of the total bend represented by unity as a numerator and the total number of crimps in the length of 120 125 130

the pipe as a denominator. The pressure on the quadrant plate is timed to take place when the crimpers have been slightly withdrawn from the crimp they have formed. 5 This frees the crimper at the inner side of the bend so that it does not interfere with the compression of the crimp at the inner side of the bend in the pipe.

While the mechanism may be thrown out 10 of gear by hand when an elbow is finished I prefer to employ automatic means as shown in Figs. 2 and 10 of the drawings. On the frame of the machine I pivot a bell crank lever 51. One arm of this bell crank lever lies against the hand lever 77 of the clutch shifting mechanism 8, which is bent to bring it to a suitable position (see Figs. 1 and 2). The other end of the bell crank lever is adapted to be engaged by the spring 20 actuated latch 53 carried by one of the crimpers 30. This latch is normally retracted so that it will not engage the lever 51, but may be forced out into an engaging position in the following manner. A lever 25 62 is suitably fulcrumed on the crimper intermediate its ends. The inner end engages behind the end of the latch 53. This latch has a head 63 formed at its inner end which is engaged by the coil spring 64 which engages also the shoulder on the support 65 in which the latch is slidable. The spring 30 normally tends to retract the latch to disengage it from the lever 51. The other end of the lever 62 is engaged by the lower end of the lever 66 fulcrumed intermediate its ends 35 on the crimper. Its upper end is pivotally connected with the inner end of a shifter 67 slidable in the crimper. The outer end of the shifter has a finger 68 secured thereon by means of a set screw 69 whereby the 40 position of the finger may be adjusted. This finger 68 is set in such a position that when the last bend in the pipe has been 45 formed it will be engaged by the edge of the segment 33. The shifter 67 is thus pushed in and through the train of levers described forces out the latch 53 so that its end lies in the path of the lever 51. This occurs while the crimpers are in contact with the 50 pipe. As the crimpers move outwardly to release the pipe the latch 53 rocks the lever 51 and throws out the clutch. The coil spring 54 connected to the lever 51 and to a stationary part returns the lever to its 55 normal position when the bent length of pipe is removed and the segment 33 therefore disengaged from the finger 68. As the head 13 must now be moved back for the 60 insertion of a fresh length of pipe it is necessary to withdraw the sliding dog 26 from engagement with the shifter bar 27. I prefer that this shall be accomplished automatically at the same time that the clutch is thrown out. For this purpose I 65 provide the following mechanism: A link

70 is pivotally connected with the lever 77, and at its other end is pivotally connected with the rock arm 71 secured to the rock shaft 72 journaled on the frame of the machine. This rock shaft carries the tappet 73 engaging a projection 74 formed on a connecting piece 75 secured to the tail of the dog 26. The parts are so timed and proportioned that the dog is thrown out at the same time as the clutch. After the elbow is 75 finished and the clutch and feed dog thrown out as described, the link 41 is thrown back and the frame 43 swung out of the way. The hand lever 61 is thrown up to release the finished pipe from the sliding head 80 13. The finished elbow may then be withdrawn and the new length of pipe inserted. The segment 33 is then clamped to the new length of pipe and the apparatus is in position for the commencement of a new series 85 of crimping and bending operations.

Figs. 14 to 19 illustrate an attachment intended to prevent the surging of the metal under the lateral push of the crimpers which tended to produce disfiguring ripples in the 90 sides of the elbow. For this purpose I provide what may be termed clamps 78 arranged diametrically opposite one another above and below the elbow at the point of crimping. Each clamp is arranged to embrace the adjacent edges of the crimpers 30 and has its face formed on an arc of a circle so that when a crimp is being formed, it will fit closely to the surface of the elbow at each side of the crimp. These clamps are 95 vertically movable, each being pivoted on a stem 79 movable in a slot in the frame of the machine. A coil spring 80 is fitted on each stem between the frame and a collar 81 and tends to withdraw the clamp from 100 its operative position.

In order to draw the clamps into engagement with the elbow as the crimpers advance, I form at each side of each clamp a beveled face 82. These faces are engaged by the 110 beveled faces 83 of pieces 84 formed on or secured to the crimpers 30. The parts are so proportioned that the clamps move approximately one quarter of the travel of the crimpers. The pivoting of the clamps on the stems 79 permits of the clamps being brought down in close contact with the elbow without any side strain on the stems.

What I claim as my invention is:—

1. In a pipe crimping and bending machine the combination of a pipe mandrel; means for shifting a length of pipe endwise on said mandrel with a stepwise movement; crimping mechanism acting adjacent the end of the mandrel; means for actuating said crimping mechanism after each forward shift of the pipe; a single bending segment clamped to the end of the pipe and projecting in front thereof; a swinging frame pivoted vertically on the frame of the 125 130

machine at the front thereof and at one side; a vertical friction bar carried thereby adapted to engage the bending segment nearly tangentially; and means for moving 5 said frame to cause the friction bar to strike the segment and slightly bend the pipe.

2. In a pipe crimping and bending machine the combination of a pipe mandrel; means for shifting a length of pipe endwise 10 on said mandrel with a stepwise movement; crimping mechanism acting adjacent the end of the mandrel; means for actuating said crimping mechanism after each forward shift of the pipe; a single bending segment 15 clamped to the end of the pipe and projecting in front thereof; a swinging frame pivoted vertically on the frame of the machine at the front thereof and at one side; a vertical friction bar carried thereby provided 20 with a grooved wearing plate adapted to engage the bending segment nearly tangentially and embrace the edge thereof; and means for moving said frame to cause the friction bar to strike the segment and 25 slightly bend the pipe.

3. In a pipe crimping and bending machine the combination of a pipe mandrel; means for shifting a length of pipe endwise on said mandrel with a stepwise movement; 30 crimping mechanism acting adjacent the end of the mandrel; means for actuating said crimping mechanism after each forward shift of the pipe; a bending segment clamped to the end of the pipe; a swinging frame 35 pivoted on the frame of the machine; a friction bar carried thereby adapted to engage the bending segment; means for moving said frame to cause the friction bar to strike the segment and slightly bend the 40 pipe comprising a lever having a flexible connection with the swinging frame, and a rotary cam adapted to engage and rock the said lever.

4. In a pipe crimping and bending machine the combination of means for holding 45 a length of pipe; means for producing a series of crimps therein; means for slightly bending said pipe after the production of each crimp comprising a single bending segment 50 clamped to the end of the pipe and projecting in front thereof; a swinging frame pivoted vertically on the frame of the machine at the front thereof and at one side; a vertical friction bar carried thereby 55 adapted to engage the bending segment nearly tangentially; and means for moving said frame to cause the friction bar to strike the segment and slightly bend the pipe.

5. Bending mechanism for pipes comprising 60 a segment adapted to be clamped to a pipe end; a swinging frame pivoted on the frame of the machine; a friction bar carried thereby adapted to engage the segment; a lever pivoted on the frame of the machine; a cam adapted to rock the lever;

a pin on the lever; a notched link adapted to engage the pin; and a universal joint connection between the link and the friction bar.

6. Bending mechanism for pipes comprising 70 a segment adapted to be clamped to a pipe end; a swinging frame pivoted on the frame of the machine; a friction bar carried thereby adapted to engage the segment; a lever pivoted on the frame of the machine; 75 a cam adapted to rock the lever; a pin on the lever; a notched link adapted to engage the pin; a universal joint connection between the link and the friction bar; a fixed collar on the pin; and a movable spring actuated 80 collar on the pin, between which collars the link engages the pin.

7. Bending mechanism for pipes comprising 85 a segment adapted to be clamped to a pipe end; a swinging frame pivoted on the frame of the machine; a friction bar carried thereby adapted to engage the segment; a lever pivoted on the frame of the machine; a cam adapted to rock the lever; a pin on the lever; a notched link adapted to engage 90 the pin; a universal joint connection between the link and the friction bar; and a shoulder on the friction bar adapted to engage beneath the segment.

8. In a pipe crimping and bending machine the combination of a pipe mandrel; means for shifting a length of pipe endwise on said mandrel with a stepwise movement; crimping mechanism acting adjacent the end of the mandrel; means for actuating 100 said crimping mechanism after each forward shift of the pipe; means acting on the outer end of the pipe for slightly bending said pipe each time a crimp is formed; driving means including a clutch; and automatic 105 means controlled by the movement of the free end of the pipe for throwing the last clutch out of gear subsequent to the last bending movement.

9. In a pipe crimping and bending machine the combination of a pipe mandrel; means for shifting a length of pipe endwise on said mandrel with a stepwise movement; crimping mechanism acting adjacent the end of the mandrel; means for actuating 110 said crimping mechanism after each forward shift of the pipe; means acting on the outer end of the pipe for slightly bending said pipe each time a crimp is formed; including a segment clamped to the end of 115 the pipe; automatic means controlled by the contact therewith of said segment for throwing the clutch out of gear subsequent to the last bending movement.

10. In a pipe crimping and bending machine the combination of a pipe mandrel; means for shifting a length of pipe endwise on said mandrel with a stepwise movement; crimping mechanism acting adjacent the end of the mandrel; means for actuating 125

- said crimping mechanism after each forward shift of the pipe; means acting on the outer end of the pipe for slightly bending said pipe each time a crimp is formed including 5 a segment clamped to the end of the pipe; automatic means, normally inoperative, but operable by the crimping mechanism for throwing out the clutch; and means actuated by the bending segment after the last bending 10 movement for conditioning said clutch shifting means for operation.
11. In a pipe crimping and bending machine the combination of a pipe mandrel; means for shifting a length of pipe endwise 15 on said mandrel with a stepwise movement; crimping mechanism acting adjacent the end of the mandrel; means for actuating said crimping mechanism after each forward shift of the pipe; means acting on the outer 20 end of the pipe for slightly bending said pipe each time a crimp is formed; automatic means, normally inoperative, but operable by the crimping mechanism for throwing out the clutch; and means actuated by the 25 last bending movement of the outer end of the pipe for conditioning said clutch shifting means for operation.
12. In a pipe crimping and bending machine the combination of a pipe mandrel; 30 a toothed shifter bar adapted to shift a length of pipe endwise on the mandrel; a ratchet dog normally engaging said shifter bar and movable to impart a stepwise movement thereto; crimping mechanism acting 35 adjacent the end of the mandrel; means for actuating said crimping mechanism after each forward shift of the pipe; means for slightly bending the pipe each time a crimp is formed; and means controlled by the 40 movement of the free end of the pipe for automatically withdrawing the dog from engagement with the shifter bar subsequent to the last bend in the pipe.
13. In a pipe crimping and bending machine the combination of a pipe mandrel; a toothed shifter bar adapted to shift a length 45 of pipe endwise on the mandrel; a ratchet dog normally engaging said shifter bar and movable to impart a stepwise movement thereto; crimping mechanism acting adjacent the end of the mandrel; means for actuating said crimping mechanism after each forward shift of the pipe; means for slightly 50 bending the pipe each time a crimp is formed; driving means including a clutch; 55 and means controlled by the movement of the free end of the pipe for automatically throwing the clutch out of gear and withdrawing the dog from engagement with the shifter bar subsequent to the last bend in the pipe.
14. Pipe crimping mechanism comprising a pair of opposed slideable plates notched to embrace the pipe; and a pair of opposed clamps arranged to slide in a direction at 60 right angles to the direction of movement of the said plates, embracing the sides of the same and having curved faces adapted to engage the pipe at each side of a crimp being formed. 70
15. Pipe crimping mechanism comprising a pair of opposed slideable plates notched to embrace the pipe; a pair of opposed clamps arranged to slide in a direction at right angles to the direction of movement of the 75 said plates, embracing the sides of the same and having curved faces adapted to engage the pipe at each side of a crimp being formed; beveled faces formed on the clamps; and beveled faces formed on the crimpers 80 adapted to engage the faces on the clamps and press the clamps inwardly when the crimpers are advanced to form a crimp.
16. Pipe crimping mechanism comprising a pair of opposed slideable plates notched to 85 embrace the pipe; a pair of opposed clamps arranged to slide in a direction at right angles to the direction of movement of the said plates, embracing the sides of the same and having curved faces adapted to engage 90 the pipe at each side, of a crimp being formed; stems carrying said clamps and slideable in the frame of the machine; springs engaging the frame and the stems tending to retract the clamps; beveled faces formed 95 on the clamps; and beveled faces formed on the crimpers adapted to engage the faces on the clamps and press the clamps inwardly when the crimpers are advanced to form a crimp. 100
